UNITED STATES PATENT OFFICE.

RUSSELL A. TRACE, OF DAYTON, OHIO, ASSIGNOR TO BUCKEYE IRON AND BRASS WORKS,
OF DAYTON, OHIO, A CORPORATION OF OHIO.

GATE-CONTROLLING DEVICE FOR COOKERS.

1,254,745.

Specification of Letters Patent. Patented Jan. 29, 1918.

Application filed April 19, 1917. Serial No. 163,164.

To all whom it may concern:

Be it known that I, RUSSELL A. TRACE, a citizen of the United States, residing at Dayton, in the county of Montgomery and State of Ohio, have invented certain new and useful Improvements in Gate-Controlling Devices for Cookers, of which the following is a specification, reference being had therein to the accompanying drawing.

10 This invention relates to the treatment of material, particularly oil bearing material, so as to render it in a shape in which the oil may be extracted therefrom. It provides particularly an improvement on a prior patent to the applicant, No. 1,115,133, Oct. 27, 1914. This patent shows a gate controlling device for cookers, the construction being such that a plurality of receptacles or compartments are provided through which the oil bearing material passes in succession. The patented invention has to do with means for automatically opening the gates between the receptacles in a prescribed order and to stop the operation of the gate opening mechanism at certain times.

15 20 25

The object of the present invention is to improve the prior construction by providing means whereby a more certain filling of the lowest receptacle or cooker is attained, thus compelling the meal to be properly cooked or put in condition to have the oil pressed therefrom. The invention provides a mechanism which maintains the gate operating devices in operation until the lower receptacle contains as much material as is desired. To this end there is provided a driving mechanism for the gate operating devices with means constantly tending to connect the two mechanisms. The level of the material in the lowest receptacle serves to control the operation of this connecting means by preventing the operation of the devices which constantly tend to cause such connection.

30 35 40 45

In the drawings, Figure 1 shows a side elevation of a cooking mechanism, the device being shown as comprising receptacles one over the other in the customary form. This figure shows the mechanism when an operation has just been started.

50 Fig. 2 is a similar side elevation of the device but showing it in position just before it may be stopped or in other words just as

the material in the lowest receptacle is high enough to answer the desired purpose.

Fig. 3 is a top plan view showing the parts when the operating devices are being driven.

Fig. 4 is an enlarged detail view of the parts shown in Figs. 1 and 2, the parts acting as a locking device.

As far as the cooking receptacles themselves and the means for passing material through them in succession are concerned the present construction is substantially like that of the prior patent. Thus a base 1 serves to support the receptacles, the lowest one of which is marked with numeral 2 and the next higher with the numeral 3. As many vertically arranged receptacles as desired may be employed. In the floor or base of each receptacle is an opening 43 closed normally by a gate 42 under the opening. These gates are carried on pins 39 and are normally held in a horizontal position so that downward passage of the material is prevented, by levers 38 to which weights 41 are attached. The weights 41 serve to maintain the gates 42 in a horizontal position, but are constructed to be raised so as to depress these gates and when so raised assume the position of the weighted lever shown in dotted lines in connection with the receptacle 3 in Fig. 1.

To operate these gates a chain 24 passes around a sprocket 25 at its lower end and around a similar sprocket, not shown, at its upper end. The sprocket 25 is carried fast on a shaft 26 which has fast therewith a large gear 27. The large gear 27 is rotated by mechanism which is substantially like that of the patent and therefore need not be particularly described. As shown, a driving belt passes around a loose pulley 6 or a tight pulley 5 on a shaft 4. The shaft 4 carries a cone pulley from any of the steps of which a belt passes to a similar cone pulley 28 which is connected through gearing including a pair of bevel gears and a worm wheel with the large gear 27. Thus, as long as the driving belt is on the tight pulley 5 the gear 27 and the chain 24 will be driven. Carried on the chain 24 is an angle lug 37 positioned to engage arms 40 fast on pins 39. Fig. 1 shows the lug 37 in engagement with one of the arms 40 and it will be understood that the further elevation of lug 37 rocks the arm 40, the

weighted lever 38 and the gate 42 to the position shown in dotted lines. At this point the weighted lever 38 is held by an arm 44 pivoted on a pin 45 and thus the gate 42 remains depressed until the lug 37 strikes the upper end of lever 44 and rocks it. This rocking movement of lever 44 carries the weight 41 over the pin 39 and then this weight may elevate the gate 42 to the full line position, thus preventing the meal from passing downward from the receptacle. To permit the weighted lever 38 to drop easily any shock absorbing device, such as indicated by numeral 46 and shown as a spring, may be provided.

In order to shift the belt from the tight pulley 5 to the loose pulley 6 and the reverse, a belt shifter 7 is mounted on a rod 8 which is connected to a bell crank lever 10. This lever may be carried on a bracket 12 fixed to the receptacle frame and a spring 9 tends constantly to move the belt shifter 7 so as to carry the driving belt on to the fixed pulley 5. The bell crank lever 10 is connected by a link 11 to a lever 13 pivoted on a pin 14 to some element of the receptacle and on the lower end of this lever 13 is mounted a by-pass pawl 16. This pawl is provided with a lug 17 engaging the lever 13 and is pivoted to the lever by a pin 15. The weight of the pawl 16 is such that it tends to assume a position wherein the lug 17 engages the edge of the lever 13.

It will be seen that rocking lever 13 will shift the driving belt to the loose pulley and to accomplish this function a weighted lever 32 is pivoted on a pin 33. A weight 34 maintains the lever in the position of Fig. 1 and the lever 32 is provided with an angled lug 36 in the path of the lug 37 on the chain 24. In the position of Fig. 2 for example, the lug 37 will shortly engage the lug 36 on the lever 32 and rock it around the pin 33. The depression of the other end 35 of this lever will rock the by-pass pawl 16 idly on its pivot 15. When the lug 37 passes away from lug 36 the weight 34 quickly depresses lever 32, thus elevating the other end 35 thereof. In this position 50 of the parts the pawl 16 cannot rock on its pivot and the lever 34 therefore passes up the cam edge of this pawl and rocks the lever 13 in a counter-clockwise direction, as seen in Fig. 2. This rocking moves the belt to the loose pulley and if it is maintained in that position will cause the stopping of the operation. However, the spring 9 constantly tends to move the driving belt to the tight pulley 5 and thus the lever 13 would simply rock back under the tension of this spring 9.

To prevent such return movement of lever 13 at proper times the lever is provided with a pin 20 adapted to be engaged by a notch 19 in a finger 18. This finger con-

stitutes a latch turning freely on a shaft 21, on the end of which shaft is fast a blade 22 adapted to rest on the meal in the lowest receptacle. A pin 22' is fast to shaft 21 and contacts with a lug 23 in the finger 18 just before the blade 22 reaches the position of Fig. 1. Then as blade 22 continues its downward movement the pin 22' through engagement with lug 23 elevates the latch 18. When the blade 22 is restored toward the position of Fig. 1 the latch 18 may be permitted to drop.

Referring to Fig. 2 in which the blade 22 is shown in a horizontal position it will be seen that the lower side of finger 18 rests on the pin 20 in lever 13. When this lever 13 is rocked by the lever 32 as before described the pin 20 is moved to the right and finally comes under the notch 19 in the finger 18. The finger promptly drops and thus return of lever 13 is prevented and the driving belt is maintained on the loose pulley 6. Withdrawal of the meal from the lowest receptacle permits the blade 22 to drop to the vertical position of Fig. 1, thus releasing the finger 18 from the lever 13, whereupon spring 9 may restore the driving belt to the tight pulley 5 and the operation of the machine start again.

It will be seen that in the normal operation of the device a complete movement of chain 24 through its path will finally elevate the lever 32 and stop the operation of the machine provided a sufficient quantity of meal has been deposited in the lowest receptacle. If, however, there has been an insufficient quantity so deposited the operation will not cease but the driving belt will be simply momentarily moved to the loose pulley 6 and then immediately restored to the tight pulley by the spring 9. Thus a second circuit of chain 24 is caused and additional material thereby deposited in the lowest receptacle from the receptacles higher up. This operation will continue until a sufficient quantity of meal in the lowest receptacle brings the blade 22 toward the position of Fig. 2 and then the completion of the circuit of lug 37 will cause stoppage of the mechanism.

In the prior patent the construction was such that the mechanism was stopped at each complete circuit of the chain corresponding to the chain 24 in this application. Thus, if a sufficient quantity of meal had not been deposited in the lowest receptacle it was necessary to set the parts by hand so as to cause a second circuit of the chain. The present invention therefore improves that prior construction by providing automatically for such a second circuit of the chain 24 if that is required.

As in the prior patent the chain 24 may be compelled to move properly by a guard 31 surrounding the side of the chain which

moves upwardly. This guard may carry a pin 30 near its lower end which serves to limit the downward movement of the controlling lever 32.

5 Having thus fully described my invention, what I claim as new and desire to secure by Letters Patent, is:—

1. In a cooker, the combination, with a plurality of receptacles adapted to discharge 10 material in succession from the first to the last receptacle, and devices for stopping the discharge of said material, of means for operating said devices, and means for connecting power to said operating means and 15 disconnecting it therefrom, said connecting and disconnecting means being so arranged that the power will be disconnected from said operating means after the discharge from the first receptacle has been stopped 20 and being arranged to connect the power to said operating means if the material in the last receptacle has not reached a predetermined height.

2. In a cooker, the combination, with a 25 plurality of receptacles adapted to discharge material from the preceding receptacle into the succeeding receptacle, and means for stopping the discharge of material, of mechanism for operating said stopping means, 30 means for stopping said operating mechanism so arranged that said operating mechanism will continue in operation until the material in the last receptacle has reached a predetermined height.

3. In a cooker, the combination, with a 35 plurality of receptacles adapted to discharge material from the preceding receptacle into the succeeding receptacle, and means for stopping the discharge of material, of mechanism for operating said stopping means, 40 means for stopping said operating mechanism so arranged that said operating mechanism will continue in operation until the material in the last receptacle has reached a predetermined height, and means for locking 45 the operating mechanism against further operation until the material in the last receptacle falls below said predetermined height.

4. In a cooker, the combination, with a 50 plurality of receptacles adapted to discharge material in succession from the first to the last receptacle, and devices for stopping the discharge of said material, of means for operating said devices, means for connecting power to said operating means and disconnecting it therefrom, said connecting and disconnecting means being so arranged that the power will be disconnected from said 55 operating means after the discharge from the first receptacle has been stopped and being arranged to connect the power to said operating means if the material in the last receptacle has not reached a predetermined height, and locking mechanism for locking 60

said operating means against further operation when the material in the last receptacle reaches said predetermined height and until the material falls below said height.

5. In a cooker, the combination, with a 70 plurality of receptacles, and gates therebetween permitting the movement of material through said receptacles from the first to the last, of means for operating said gates in succession, a constantly moving motor 75 mechanism, means for connecting said motor mechanism to said gate operating means, said means constantly tending to assume a connecting condition, and devices, controlled by the material in the last receptacle, for 80 preventing said connecting means from acting.

6. In a cooker, the combination, with a 85 plurality of receptacles, and gates therebetween permitting the movement of material through said receptacles from the first to the last, of means for operating said gates in succession, a constantly moving motor mechanism, means for connecting said motor mechanism to said gate operating means, 90 said means constantly tending to assume a connecting condition, means, whereby said gate operating mechanism at the end of each complete operation thereof, may disconnect said motor mechanism from said gate operating means, and devices, controlled by the material in the last receptacle, for preventing such disconnection of said motor mechanism from said gate operating means.

7. In a cooker, the combination, with a 100 plurality of receptacles, each upper receptacle having a discharge opening leading to the next lower receptacle, gates to control the respective discharge openings, and actuating devices for imparting movement 105 to said gates, of a controlling device having a part to successively engage the actuating device for each of said gates and successively open said gates, means for closing each of said gates before the next gate is opened, 110 means to start into operation said controlling device upon the material in the lowest receptacle falling below a predetermined point, and means to stop said controlling member irrespective of the height of the 115 material in the lowest receptacle.

8. In a cooker, the combination, with a 120 plurality of receptacles, each receptacle having a discharge opening leading to the next lower receptacle, gates to control the respective discharge openings and actuating devices for imparting movement to said gates, of a controlling device comprising a vertically movable member and a tripping block adapted to successively engage the 125 actuating device for each of said gates, means to start in operation said controlling device when the material in the lowest receptacle has fallen below a predetermined level means to stop said controlling 130

device without respect to the material in said lowest receptacle, and means to lock said controlling device in stopped position.

9. In a cooker, the combination, with a plurality of receptacles, each upper receptacle having a discharge opening leading to the next lower receptacle, gates to control the respective discharge openings and actuating devices for imparting movement to said gates, a controlling device comprising a flexible member supported adjacent to said cooker, means for imparting lengthwise movement to said flexible member, a tripping block carried by said flexible member, a blade pivoted in the lowest receptacle resting upon the surface of the material therein, adapted to unlock a means to shift a power belt into operative position to operate said flexible member when the material in said lowest receptacle falls below a predetermined level.

10. In a cooker, the combination, with a plurality of receptacles, each upper receptacle having a discharge opening leading to the next lower receptacle, gates to control the respective discharge openings and actuating devices for imparting movement to said gates, a controlling device comprising a flexible member supported adjacent to said cooker, means for imparting lengthwise movement to said flexible member, a tripping block carried by said flexible member, a blade pivoted in the lowest receptacle resting upon the surface of the material therein, adapted to unlock a means to shift a power belt into operative position to operate said flexible member when the material in said lowest receptacle falls below a predetermined level, and means actuated by said tripping block to shift said power belt into inoperative position.

11. In a cooker, the combination, with a plurality of receptacles, each upper receptacle having a discharge opening leading to the next lower receptacle, gates to control the respective discharge openings and actuating devices for imparting movement to said gates, a controlling device comprising a flexible member supported adjacent to said cooker, means for imparting lengthwise movement to said flexible member, a tripping block carried by said flexible member, a blade pivoted in the lowest receptacle resting upon the surface of the material therein, adapted to unlock a means to shift a power belt into operative position to operate said flexible member when the material in said lowest receptacle falls below a predetermined level, means actuated by said tripping block to shift said power belt into inoperative position, and means to lock said power belt shifting device in inoperative position.

12. In a cooker, the combination, with a plurality of receptacles, each upper recep-

tacle having a discharge opening leading to the next lower receptacle, gates to control the respective discharge openings, actuating devices for imparting movement to said gates, a controlling device comprising a vertically movable member, and a part carried by said member to successively engage the actuating device for each of said gates to open that gate, a blade resting upon the surface of the material in the lowest receptacle adapted to unlock a power belt shifting device and to permit said power belt to operate said controlling device.

13. In a cooker, the combination, with a plurality of receptacles, each upper receptacle having a discharge opening leading to the next lower receptacle, gates to control the respective discharge openings, actuating devices for imparting movement to said gates, a controlling device comprising a vertically movable member, and a part carried by said member to successively engage the actuating device for each of said gates to open that gate, a blade resting upon the surface of the material in the lowest receptacle adapted to unlock a power belt shifting device and to permit said power belt to operate said controlling device, and means operable by said controlling device to reshift said belt shifting device to place the belt in inoperative position to stop said controlling device irrespective of the level of the material in the lowest receptacle.

14. In a cooker, the combination, with a plurality of receptacles, each upper receptacle having a discharge opening leading to the next lower receptacle, gates to control the respective discharge openings, actuating devices for imparting movement to said gates, a controlling device comprising a vertically movable member, a part carried by said member to successively engage the actuating device for each of said gates to open that gate, a blade resting upon the surface of the material in the lowest receptacle adapted to unlock a power belt shifting device and to permit said power belt to operate said controlling device, means operable by said controlling device to reshift said belt shifting device to place the belt in inoperative position to stop said controlling device irrespective of the level of the material in the lowest receptacle, and means to lock said belt shifting device in inoperative position.

15. In a cooker, the combination, with a plurality of receptacles, each receptacle having a discharge opening leading to the next lower receptacle, gates to control the respective discharge openings, and actuating devices for imparting movement to said gates, of a controlling device comprising a vertical, movable member and a tripping block adapted to successively engage the actuating device for each of said gates, a blade

pivoted in said lowest receptacle adapted to ride on the top of the material in said receptacle, a finger pivoted on the same shaft with said blade with a lug thereon adapted 5 to be elevated when a similar lug on said blade comes in contact therewith upon the lowering of the level of the material in said receptacle, a belt shifting lever, resilient means for holding said belt shifting lever 10 in operative position to operate said controlling device, a locking means between said finger and said belt shifting device when the material falls below a predetermined level, and means to lock the same actuated 15 by said controlling device irrespective of the level of the material in the lowest receptacle.

16. In a cooker, the combination, of a plurality of receptacles, gates therebetween 20 adapted to permit the passage of material from one receptacle to the other, a controlling device to operate said gates, a power pulley fixed to a power shaft, a loose pulley on said shaft, shifting means normally holding 25 a belt on said power pulley, a lock in said lowest receptacle adapted to keep said shifting means in inoperative position, a blade in said lowest receptacle resting on the surface of the material therein adapted to unlock 30 said lock when the material falls below a predetermined level, a pivoted weight on the end of said belt shifting means adapted to move in one direction and not in the other, a lever pivoted adjacent 35 said belt-shifting means adapted to be actuated by the gate controlling device and to operate on said weight and said belt-shift-

ing means to throw it into locked position to shift the belt into inoperative position and stop the gate-operating means. 40

17. In a cooker, the combination, of a plurality of receptacles, gates therebetween, a pulley fixed to a shaft connected to a source of power, a companion pulley traveling loosely on said shaft, a shifting fork 45 to move a belt from one pulley to the other, means to normally hold said belt on the pulley fixed to the shaft, means to lock said shifting means by a finger engaging a pin on said shifting means, a blade pivoted in 50 the lowest receptacle riding on the surface of the material therein, adapted to unlock said finger when the material falls below a predetermined level, means to open said gates, set in operation when said shifting 55 means is unlocked, a second means operated by said gate shifting means adapted to lock said belt shifting means and stop the movement of the gate opening means.

18. In a cooker, the combination, with a 60 plurality of receptacles, and means permitting the gravity discharge of material in each receptacle to the next in succession, devices, controlled by the level of the material in the lowest receptacle, for controlling the 65 operation of said means, said devices constantly tending to cause operation of said discharge means, and being restrained from causing such operation when the material in said lowest receptacle is at a predetermined 70 level.

In testimony whereof, I affix my signature.

RUSSELL A. TRACE.
